ANESTHESIA TRAY

Charles M. Huck, Bound Brook, N.J., assignor to Mc-
Neil Laboratories, Inc., a corporation of Pennsylvania

Filed May 15, 1969, Ser. No. 17,163

Term of patent 14 years

Int. Cl. D24—02

U.S. Cl. D83—1

FIG. 1 is a top view of the cabinet;

FIG. 1 is a perspective view of an anesthesia tray;

FIG. 2 is a top plan view of FIG. 1 at an enlarged scale;

FIG. 3 is a front elevation of FIG. 2 partly in staggered section and taken on lines 3-3 of FIG. 2;

FIG. 4 is a rear view of FIG. 1;

FIG. 5 is a rear view section taken on lines 5-5 of FIG. 2;

FIG. 6 is a side elevational view looking from the left of FIG. 1;

FIG. 7 is a vertical cross section view taken along the lines 7-7 of FIG. 2; and

FIG. 8 is a side elevational view looking from the right of FIG. 1.

I claim:

The ornamental design for an anesthesia tray, as shown and described.
